[57] CLAIM

The ornamental design of the earring clearance telephone handset earpiece or similar article, as shown and described.

DESCRIPTION

FIG. 1 is a reduced size front and right side perspective view of an earring clearance telephone handset earpiece or similar article;

FIG. 2 is a front end, right side and underneath perspective view thereof;

FIGS. 3 and 4 are respectively front elevational and right side elevational views thereof;

FIG. 5 is a rear elevational view thereof; and

FIGS. 6 and 7 are respectively front bottom and top plan views thereof.

The broken line showing of a front and right side perspective view of a telephone handset and an abbreviated portion of coiled cord in FIG. 1 is for illustrative purposes only and forms no part of the claimed design.
